UNITED STATES PATENT OFFICE.

CHARLES G. KNIGHT, OF COLUMBUS, OHIO.

PICTURE-FRAME FOR MONUMENTS.

SPECIFICATION forming part of Letters Patent No. 269,429, dated December 19, 1882.
Application filed March 25, 1882. (No model.)

To all whom it may concern:

Be it known that I, CHARLES G. KNIGHT, a citizen of the United States, and a resident of Columbus, in the county of Franklin and State 5 of Ohio, have invented a new and valuable Improvement in Picture-Frames for Monuments; and I do hereby declare that the following is a full, clear, and exact description of the construction and operation of the same, reference 10 being had to the annexed drawings, making a part of this specification, and to the letters and figures of reference marked thereon.

Figure 1 of the drawings is a representation of a front or face view of my improved picture-frame, and Fig. 2 is a vertical sectional view of the same.

This invention has relation to metallic encasements or picture-holders for tombstones and vaults; and it consists in the novel construction and arrangement of parts, as will be hereinafter fully described, and particularly 20 pointed out in the claim.

In the accompanying drawings, the letter *a* designates a rim-case, of elliptical or other 25 form, having projecting from its margin perforated portions *b*, through which fastening screws or pins *c* are passed into cement-filled recesses in the face of the tombstone, thereby permanently securing the case in position. 30 The rim-case *a* is formed with an inner ledge or shoulder, *d*, on which the glass *e* is supported and around which extends an inner-projecting edge wall, *g*, forming the inner wall of the annular recess *h*, which is formed in the 35 back of the rim. The edge wall, *g*, serves as a seat for the rear cap-plate, *k*, which is made with an overlapping rim, designed to fit over

said edge wall, thereby covering in securely the glass and the picture, which is placed in the recess back of the glass. The glass is secured on the ledge *d* by means of plaster-of-paris or other cement, the picture put in place behind the glass, and held thereto by the cap-plate *k*, closing over the edge wall, *g*. A heavy convex front cover-plate, *m*, is pivoted to the 40 rim-case by means of a headed rivet, *n*, which extends through the rim into the rear recess, *h*. Projections or studs *s* are formed in the recess *h*, and serve to aid in holding the cement or plaster with which the recess is entirely filled after the picture is in position and duly protected by the rear cap-plate. The 45 front plate serves to protect the glass from being broken, and defends the picture from the action of the direct rays of the sun.

Having described this invention, what I claim, and desire to secure by Letters Patent, is—

In a picture-holder for tombstones and the like, the combination, with the rim *a*, having 50 the perforated projections *b*, the inner ledge or shoulder, *d*, and the inner-projecting edge wall, *g*, forming the recess *h*, of the glass *e*, cemented to the shoulder *d*, and the cap-plate *k*, fitting the edge wall, *g*, substantially as 55 specified.

In testimony that I claim the above I have hereunto subscribed my name in the presence of two witnesses.

CHARLES GODFREY KNIGHT.
